APPARATUS FOR MAKING PATTERNED
STABLE PLYWOOD

Howard C. Soehner, Louisville, Ky., assignor to
The Mengel Company, Louisville, Ky., a corpora-
tion of New Jersey

Original application March 18, 1949, Serial No.
82,103. Divided and this application June 11,
1949, Serial No. 98,464

2 Claims. (Cl. 144—281)

1

This invention relates to improvements in apparatus for forming a pattern of design in plywood concurrently with the making on a commercial production basis, of stable plywood panels from veneers that will retain substantially their original areas and a planar state indefinitely by reason of the fibres thereof having been deprived of their natural properties that cause warpage, shrinkage and twisting without developing noticeable checks or splits in the surface of finished panels. This is a division of my application, Serial Number 82,103, filed March 18, 1949, and entitled "Method of Making Plywood and a Product Thereof."

In the aforesaid application there are disclosed apparatus, the method of using the same to produce panels and two patterns therefor.

The object of this invention is to provide a novel platen or caulk plate for use in a press provided with means for heating the same during production of panels of the types shown therein and reproduced herein, and kindred types.

Another object of this invention is to construct said platen or caulk board so that the same can liberate instantaneously the steam and vapors from veneers having a moisture content near or above the fibre saturation point (hereinafter sometimes referred to as "wet veneer") when suddenly subjected to high temperatures and without forming blisters or producing cracks or voids that may be caused from trapped or confined steam.

These and other objects will be apparent to those skilled in the art as the following description is read in connection with the accompanying drawings, on an enlarged scale in terms of a plywood panel, in which:

Figure 1 is a perspective sectional view through a press closed on a fragment of an assembly of veneers for making a three-ply panel on which is superimposed one form of my novel caulk plate as these elements appear after requisite pressure and heat have been applied thereto for completing a panel.

Figure 2 is a perspective view of a fragment of the caulk plate shown in Fig. 1.

Figure 3 is a perspective view of another form of caulk plate, however, of the same general type.

Figure 4 is a perspective view of another form of caulk plate and of a different construction.

Figure 5 is an end elevation of a fragment of the caulk plate shown in Figure 1 partially sunk into the top veneer thereof.

In Fig. 1, numerals 10, 11 and 12 designate respectively face veneer, core and bottom veneer in process of being formed into a fragment of pat-

2

terned plywood by a caulk plate 14 and the depending teeth sunken into the face veneer by requisite pressure and heat applied by and through platens 15, 15A.

In Figs. 1 and 2, caulk plate 14, the flat faced teeth depending therefrom are disposed in several series, to wit: 16, 16A, 17, 17A, 18, 18A et cetera with a relatively large space or gap between the juxtaposed ends thereof. This gap extends beyond the root of the teeth in order to provide a channel 19 that is free to function as such for the liberation of steam and vapors expelled from the application of heat.

It will be observed that in this instance these teeth penetrate the face veneer beyond the medial plane thereof and thereby apply a vastly greater area of heated surface to the wet veneer, thus producing a blast of steam greatly in excess of that expelled from caulk plates or platens not equipped with the teeth adverted to above.

In order to prevent blistering of the surface of the face ply, channels 19 are provided. As shown in the drawing these transverse channels have a depth which is greater than that of the valleys between the teeth and thus freely communicate with the ambient atmosphere even when the caulk teeth are sunken into the veneer. It should be noted that very short teeth are employed and that each tooth is flanked by channels thereby providing an easy exit for the steam that stems from the moisture entrapped in and between the wood fibres, none of which steam has to travel more than half the length of a tooth before reaching a free escape to the ambient atmosphere. It is evident that it is not necessary to have teeth of any particular shape or depth, and the penetration requirements may also vary, as more fully described in my application Serial Number 82,103, filed March 18, 1949, and entitled "Method of Making Plywood and a Product Thereof."

The pattern of the caulk plate shown in Fig. 3 is identical in principle to that explained above. This figure has been included to show that variations can be indulged. A detailed description is not regarded as being essential to grasp the teachings thereof.

The main feature in caulk plate 20 illustrated in Fig. 4, which is a departure in structure and pattern for plywood to be formed thereby, from the simpler type shown in the other figures, consists of ducts and channels in the body of said plate. Here are inserts 21, 21 overlying and disposed at right angles to major channels 22, 22 and in which inserts are smaller channels or grooves 23, 23 in the outer surface that commun-

cate through ducts 24, 24 to minor channels 23A, 23A, on the inner faces of these inserts. These latter channels lead to the major channels thereby carrying forward the same principle for venting the steam as explained for Fig. 1. Whether the teeth are inserted partially or entirely into the veneer, channels 23, 23 are not completely closed. Obviously channels 22, 22 are always open to the ambient atmosphere.

It should be noted that the teeth in the inserts are shown to have sharp edges to facilitate cutting the wood fibres perpendicularly to the grain thereof, while the other series of teeth are fashioned with flat faces to compress the fibres falling thereunder. It should also be noted that the teeth in the inserts do not project as far as the teeth which are parallel with the wood fibres.

While it will be apparent that the disclosed embodiments of my invention together with the illustrated instrumentalities and types of products produced thereby are well calculated to fulfill adequately the objects and advantages primarily stated, it is to be understood that the invention is susceptible of variations, modifications and changes within the spirit and scope of the subjoined claims.

What I claim is:

1. In a platen, caul plate or the like for forming patterned depressions in the exposed surface of the outer veneer of plywood while it has a high moisture content; a working face having several series of spaced-parallel teeth, said teeth being interrupted by and terminating in transverse channels formed within the platen and having a depth greater than that of the valleys between the teeth, said channels communicating with the ambient atmosphere when said teeth are heated and sunken into the veneer sufficiently to com-

press all of the fibers embraced by the contacting surfaces of the platen, whereby the liberated steam is compelled to flow to and through the said channels to the atmosphere.

5. 2. In a platen or caul plate or the like for forming depressions in the outer veneer for plywood or the like while the latter has a high moisture content; major ducts extending through the body of the platen, a working face thereof, said working face having a plurality of short teeth that terminate in minor transverse channels which communicate at spaced points with vertical ducts that in turn communicate with said major ducts for discharging steam liberated at the middle portions of the veneer when said teeth are hot and sunken into said outer surface sufficiently to compress all of the fibers embraced by the contacting surfaces of the platen, whereby the liberated steam is compelled to flow through the said channels and ducts to the atmosphere.
